24 Claims. (Cl. 122—11)

This invention relates to the generation and utilization of steam and especially to the generation of steam and its utilization to produce mechanical power. The invention more particularly relates to the generation of steam and the development of power from it in a prime mover of the rotary type.

Heretofore steam has commonly been generated in steam boilers arranged as separate units from which the steam may be withdrawn through pipes for use at a point remote from the boiler. When used for the production of mechanical power the steam has been carried through pipes to so-called prime movers which utilized the energy of the steam by causing its pressure to act upon a movable element of the prime mover. Commonly the steam is expanded in the prime mover from the boiler pressure to a lower pressure, usually less than atmosphere and is exhausted from the prime mover to a condenser. In such constructions not only has it been necessary to provide a large number of joints in the pipe leads and in the connections between the boiler and the prime mover, such as a turbine, but the operation of the boiler as a unit with the prime mover has not been possible. Moreover, these leads and connections and the necessary fittings result in loss of heat and in pressure losses and thus increase the cost of operation, especially in the use of high pressures. These faults contribute to the difficulties of operation and the limitation of output.

The present invention provides a novel process of generation of vapor, particularly in connection with the generation of mechanical power by a rotary prime mover and provides novel means for carrying out said process of vapor generation. Moreover, the invention makes use of the rotary action of the prime mover to provide the conditions for carrying out the process.

According to the present invention the liquid from which the vapor or the steam is to be generated is subjected to the action of centrifugal force. A mass of the liquid to be evaporated is caused to revolve about an axis and thus, as is well known, the mass will be subjected to centrifugal force of an amount which depends upon the speed of revolution. When said speed of revolution is sufficiently high, for example, is a speed such as may be provided by a rotary prime mover, the centrifugal force acting upon the mass of liquid is sufficient to produce in the liquid, when confined, a substantial pressure. This pressure, for example in the case of water, may be as great as that at which steam usually is generated for power or other purposes. In fact, it is possible to produce by this method a pressure considerably greater than that at which vapor is usually generated from water or from other liquids, such as mercury, which have been used for the generation of mechanical power. According to the in-

vention the centrifugal force or action is utilized to cause flow of the liquid or of the water through a path of liquid flow. By suitably arranging the direction of said path of liquid flow in relation to the revolution of the mass of the liquid, that is, with respect to the axis of revolution, the liquid may be caused to flow in said path outwardly from said axis under the action of the centrifugal forces due to the revolution of the mass of the liquid about the axis. Moreover, while flowing in said path under the action of centrifugal force the pressure of the liquid may be raised gradually from a relatively low pressure adjacent the axis to a considerably higher pressure at a point in the path remote from the axis.

Such a path of flow of the liquid or of the water may be provided by arranging a tube in an approximately radially relation to a shaft. If by suitable means the liquid such as water is delivered to the end of said tube adjacent the shaft and if the shaft is rotated at a suitable speed, the water will flow outwardly from said shaft through said tube under the action of centrifugal force and the pressure of the water confined in the tube will be gradually increased in a direction along the tube outwardly from the shaft. Moreover, by suitable connections to a reservoir or other water storage the rotation or revolution of the tube itself may be utilized to draw water from said reservoir and to cause the flow of the water under said centrifugal action through the tube to a point therein remote from the shaft.

If now the liquid, while subjected to centrifugal force in said path and at the pressure created therein due to centrifugal force, is subjected to vapor generating heat, vapor may be generated from the liquid at substantially the pressure to which the liquid or water has been raised by the centrifugal action. Such vapor may be generated from the liquid delivered to a path of flow for heat exchange, which path is a continuation of the path of liquid flow in which the liquid was subjected to centrifugal action.

Moreover, although the invention is not limited to flow of the vapor in any particular direction, advantageously in many cases the path of flow for such heat exchange and for vapor generation may be such that the flow of the vapor or of the mixture of vapor with the liquid from which it is being generated is opposed by the centrifugal action which produces the flow of the liquid as described. Such a path of flow for vapor generation may be inwardly toward the axis of revolution from the point in the path of liquid flow to which, under centrifugal action, the liquid has been delivered.

If a tube is used for flow of liquid or water therethrough in heat exchanging relation to a source of heat, such a tube also may be placed approximately radially with respect to a shaft

such as that above mentioned in relation to which the water flow tube was radially arranged. By such an arrangement of the tubes, as mentioned above, the water may be delivered to the shaft end 5 of the water tube and steam and any water mixed therewith may be discharged from the shaft end of the steam generating tube. By simply connecting the tubes at their ends remote from the shaft the water for steam generation may be 10 passed from the water tube to the steam generating tube. It will now be clear that substantially by this arrangement there is provided a U-tube having its ends adjacent the shaft and having the bend thereof remote from the shaft. In such a 15 tube when rotated upon said shaft at a suitable speed the water and the steam will be subjected to the centrifugal force tending to impel the mass of the water or of the steam or of the steam and water mixture outwardly toward the bend.

20 It will be apparent that if such a path of water flow, that is, such a path as is provided by a U-shaped tube, were filled in both legs of the U with water or with steam or any other fluid there would be no unbalanced force available to produce 25 flow of the fluid therethrough from one end of the path to the other; that is, first outwardly from the axis and then inwardly toward the axis. However, if one portion of the path is subjected to heat sufficiently to generate from the liquid 30 vapor which thereby will occupy, relative to the liquid, a considerable space and which therefore will have a density considerably less than the liquid from which it was evaporated, an unbalance will be produced in the centrifugal forces 35 acting respectively upon the vapor or upon the mixture of the vapor with the liquid from which it was evaporated in said heated path and in the other path upon the liquid without admixture of vapor. This unbalance, therefore, will be available 40 to produce flow of the liquid outwardly from the axis, as described above, with the corresponding increase in the pressure of the liquid, and this increase in pressure will provide the force against which the vapor by its usual expansive 45 action will flow inwardly toward the other end of the path adjacent the axis. Moreover, such an expansive flow producing action will take place while the vapor is generated at a pressure substantially equal to that which the water has been 50 raised by the centrifugal action.

Thus it is possible by the present invention to feed a liquid substantially along an axis of revolution to a path of flow so related to the axis that the liquid will flow first outwardly from the axis 55 under the action of centrifugal force and then inwardly toward the axis together with the vapor generated therefrom. To produce this flow it is necessary, however, that the substantial generation of vapor in the outward flow of the liquid 60 be prevented or limited to such a degree that it does not substantially interfere with the centrifugal action upon the liquid and with the increase in hydraulic pressure thereof. It is also necessary that for the most part the steam be generated in the portion of the path beyond said 65 portion through which the water flows outwardly from the axis. This vapor generating portion of the path may return toward the axis as stated above. Thereby the steam and any water mixed 70 therewith is opposed by the centrifugal force acting thereon, but the flow in said portion of the path is produced by the hydraulic pressure created in the water in the portion of the path in which it flows outwardly from the axis.

75 By mounting or otherwise suitably arranging

the vapor generating element, as described above, upon a shaft which is an extension of a shaft of a rotary prime mover, the requisite rotation or revolution of the element may be provided. Moreover, in such case, as will be clearly understood from more detailed description to follow in connection with the drawings, the vapor generated in the element may be utilized directly in the prime mover without first withdrawing the vapor from the element or from the vapor generator to a point outside the generator and then redelivering it to the prime mover. The vapor may be delivered along the shaft of the prime mover and then through a suitable conduit outwardly to the nozzle or other expansion device 10 for development of the power by expansion in the usual manner.

Constructions according to the invention are suitable for use with two or more fluids, for example, in the binary cycle using water and mercury, and the steam discharged from the prime mover may be used to heat the second fluid. As the rotating steam generator is especially adaptable for high pressures, the secondary steam generator may serve as a condenser for the fluid 20 evaporated in the rotary steam generator and expanded in the prime mover connected thereto. The pressures at which the primary and secondary vapors are generated are determined by the operating conditions and the purpose for which 25 the steam or vapor or the mechanical power is to be used.

In another phase of the invention provision is made for impelling the gases to flow over the rotating steam generating elements by so forming 35 the elements or providing them with blades or fins that they act as a fan or blower to propel the gases through the space in which the elements are revolving. The gases may thus be caused to flow, for example, from a furnace to a stack 40 without the use of auxiliary blowers or suction fans. The invention thus provides an efficient construction for the transfer of heat from gases moving at high velocity.

Other features and advantages of the invention 45 will be understood from the more detailed description to follow in connection with the drawings in which:

Figure 1 shows a vapor generating element of the type of the invention mounted upon a rotating shaft;

Fig. 2 shows another form of such an element;

Figure 3 shows a vapor or steam generator of the type of the invention having steam generating elements formed with a plurality of tubes 55 connected to headers;

Figure 4 is a cross section on line 4—4 of Figure 3;

Figure 5 shows an assembly of a rotating steam generator mounted upon an extension of the shaft of the prime mover;

Figure 6 shows a plant comprising a rotating steam generator with a prime mover connected thereto in combination with a common type of boiler;

Figure 7 shows a rotating vapor or steam generator connected in a fluid flow circuit;

Figure 8 shows another modification of the vapor generator of the invention;

Figure 9 is a cross section on line 9—9 of Figure 8; and

Figure 10 shows a cross section of one of the tubes of Figure 8.

Figure 11 shows an enlarged view of the rotating elements of Figure 8.

Figure 12 is a section upon line 12—12 of Figure 11.

The simplest form of operation of such a rotating steam generator is a two-legged tube, as illustrated in Figures 1 and 2. When liquid is poured into a U tube, as long as this tube is not heated the liquid in both legs remains of equal height and a state of rest is brought about. If, however, the one leg 1 of this tube is heated, which can be brought about by protecting leg 2 from the effect of hot gases by means of a separating wall, either warm water or a mixture of vapor and water is produced in the heated leg 1. The specific weight of this liquid is less than the specific weight of the unheated liquid in leg 2. The result of this is that a driving force is produced, which corresponds to the difference of weight of the column of fluid in both legs 1 and 2.

The driving force is not particularly high when the two-legged tubes are at rest. However, this force will be substantially increased if the tube is revolved or rotated, whereby the two-legged tube will be exposed to a considerably greater acceleration than the acceleration of gravity.

These conditions are illustrated in Figures 1 and 2. According to Figure 1, the liquid to be evaporated is delivered from the receptacle placed above stuffing-box 5 into the rotating hollow shaft which is rotated or revolved by suitable driving means 60, from which hollow shaft it flows into leg 2 of U-tube and from here into leg 1, whereby U-tube becomes completely filled with the liquid if the receptacle 4 is at a sufficient height.

If leg 1 is heated by gases which do not reach leg 2 because of separating wall 3, then vapor or steam is generated in leg 1 which is displaced and leaves the U-tube by way of the left end of the hollow shaft 6 and stuffing box 7.

Figure 2 shows a two-legged tube, whose legs are not parallel, but at right angles to each other. Here also the liquid is delivered from the receptacle 4 above the stuffing box 5 into the hollow part of shaft 6, which shaft is rotated, and the liquid flows from here into leg 2 of the two-legged tube. By means of gases, which heat leg 8 but are kept separate from leg 2 by separating wall 3, steam is generated in leg 8, which steam is displaced and flows out of leg 8 into collector 9 and leaves the apparatus by way of conduit 10.

In practical operation one two-legged tube, as shown in Figures 1 and 2, could naturally not deliver sufficient steam. These drawings only show that in principle it is possible to operate the process of invention by rotating two-legged tubes or tube systems of various forms if care is taken to have steam generated in only one leg of the tube or tube system and to have the zenith of the two-legged tube or tube system lying on the outer circumference of the rotating member.

As illustrated in Figures 3 and 4, a two-legged tube system having tubes 1 and 2 is arranged on the hollow shaft 6, which tube system also is brought into rotation by means of the rotation of the hollow shaft 6. The water or other liquid to be evaporated is delivered from the highly positioned receptacle 4 over the stuffing box 5 into the right end of the hollow shaft 6 and from here flows into leg 2 of the rotating tube system.

The liquid is led through distributing tubes or headers 11 into tubes 1, then flows from here by way of the tube system 13 into the left side of the hollow shaft 6, in order to leave the apparatus by way of the stuffing box 7. As long as no heat is applied to the tubes, according to the law of com-

municating tubes these tubes will become filled with water. If, however, the tubes 1 are heated, for example by conveying heating gases through the rotating system in the direction of the arrow, the steam produced will be displaced from tubes 1 and will flow over by way of the left end of the hollow shaft 6 to a place of use. Through suitable means of construction, if necessary by providing separating walls, as shown at 3 in Figure 1, between the tubes 2 on the one hand and tubes 1 on the other hand or by arranging tubes 2 in such a zone of temperature of the heating medium as to prevent steam formation at the actual pressure in tubes 2, care must be taken not to allow of any substantial steam formation in tubes 15.

If the generated steam encounters any resistance, for example through a throttle or a power machine, then the pressure of this steam increases, and the steam now displaces the water in the heated tubes 1. In the case when all the water from tubes 1 is to be displaced the necessary steam tension can be estimated. In such case it must be equal to the difference of the pressure through the centrifugal action of the water in 25 tubes 2 and the pressure through the centrifugal action of the steam in tubes 1.

If the specific weight of the water is set equal to 1 and the specific weight of the steam equal to 0.1, the diameter of the rotary member equal to 3.0 ft. and the number of rotations occurring every minute equal to 4000, then the pressure due to the centrifugal action of the water is estimated at 2530 lbs. per square inch. The pressure due to centrifugal action of the steam amounts to 253 35 lbs. per square inch. Apart from the friction in the tubes, the steam, under the assumed conditions, could be generated with a pressure of 2270 pounds per square inch.

A substantial advantage of the process of invention consists in this, that the high pressure of the water necessary for feeding is generated in the boiler itself. This results in the water delivery conduit being under only a very slight pressure, and all connections, such as stuffing 45 boxes and other fittings, need not be constructed for high pressure as is generally the case in the existing high-pressure steam generators.

The withdrawal of the steam takes place through connecting header 12 and a superheater 50 13, in which the steam is dried and superheated.

Figure 5 shows the connection of a rotating steam generator with a prime mover. The steam generator and the prime mover are coupled together in such a manner that a connected assembly results, in which steam is generated, which is expanded in the prime mover in order to generate energy. The expanded steam is discharged into a condenser or, depending on the pressure of the exhaust, steam is led into a low pressure turbine or used for heat purposes. The present construction of the steam power plant also affords the possibility of avoiding all connecting pipes together with their fittings between the steam generator and the prime mover. In this way the 65 space taken up by the entire plant becomes less than that of the existing plants, which results in a notable lowering of the cost of the plant and the costs of operation.

As illustrated in Figure 5, the rotating steam generator is arranged at the right and the turbine at the left. The liquid to be evaporated is delivered from the elevated receptacle 4 above the valve 14 and stuffing box 5 into the hollow shaft 6 of the steam generator. It then flows from here 75

by way of the tube system 2 into the distributing headers 11 and from here into the tube system 1 and is generated in the steam. Through the difference between the centrifugal action of the water and that of the steam or steam water mixture in tubes 2 and 1 a substantial increasing of pressure takes place. The steam generated in tube system 1 flows through the shaft 6 into the superheater 13, and in it is heated to the desired 10 temperature. From here it flows into the steam turbine 15.

It is advantageous to allow the steam to expand from the middle of the turbine either in axial or radial direction, as then all stuffing boxes 15 or other connecting positions under high pressure can be abolished.

The regulation of the speed of revolution may take place by means of altering the quantity of heat supplied, i. e. the quantity of fuel burned. 20 This could take place, according to Figure 5 by allowing a speed regulator 50 or a device responsive to the speed of the machine to control burner 16, or a thermostat subjected to the heat of the steam could also control the fuel delivered. For 25 example, a speed regulator 50 may be connected as by electrical means to operate fuel valve 51 or the thermostat 17 may be connected to control this valve.

The regulation of the amount of water which is 30 fed to the steam generator preferably may be accomplished in relation to the temperature of the generated steam. When this steam is delivered to a prime mover such as a turbine, as illustrated in Figure 5, the temperature utilized may be that 35 of the steam after expansion in the first stage, or the temperature may be taken at some other point in the expansion, in order to avoid placing the thermostatic element in the shaft of the steam generator. As may be seen from Figure 5 the 40 thermostatic element may be placed in the casing of the turbine and subjected to the temperature of the steam flowing from the first revolving element of the turbine. This thermostatic element 17 is connected to control the regulating valve 14. For practical purposes this may serve 45 to control the feed to the steam generator as effectively as if the thermostatic element were placed in the shaft of the apparatus at the outlet of the steam generator.

50 This thermostat is operated in such a manner that when the temperature of the steam is too high in this turbine chamber, the regulating valve 14 is opened to enable more fluid to pass into the steam generator, while if the temperature 55 of the steam is too low in said turbine chamber the regulating valve is throttled so that less fluid passes into the steam generator, thus causing the temperature of the superheated steam to rise.

As the steam power plant according to the invention must be started up by means of an auxiliary energy supply, a special starter 61 which may include a motor of suitable type is provided, such as an electric motor or steam turbine supplied from a separate source of power or of steam, which 65 sets the steam generator into rotation by starting up the whole apparatus. The pressure of the generated steam is thus considerably increased so that the turbine is driven by means of this steam and the starter can then be cut out by any 70 suitable disconnecting means or gearing which may be interposed between the starter 61 and the shaft of the rotating steam plant.

It is also possible to use the auxiliary steam which is led through conduit 18 into the first 75 turbine chamber. In this case it is necessary to

provide a check valve 19 which prevents an escape of the steam through the hollow shaft 6 to the steam generator. However, as soon as the steam in the steam generator acquires an increased pressure the check valve 19 opens itself automatically, so that the steam generated in the steam generator then flows over by way of the hollow shaft 6 and superheater 13 into turbine 15 and drives this turbine. The auxiliary steam may then be shut off.

It is hardly necessary to call attention to the fact that this steam power plant of the invention is neither limited to stationary installations nor to the evaporation of water alone. It can be used just as well for any kind of motor vehicles. It is 15 very well suited for the evaporation of mercury, since in mercury steam plants owing to the high price of mercury and the danger to health, which problems come into consideration because of leaky joints with the attendant loss of the mercury vapor, it is a question of a steam generator with the smallest possible liquid content and the greatest possible reduction in joints, all of which in the steam generator plant according to the invention is provided for in the highest degree.

Figure 6 shows an example of how, in a further embodiment of the invention, the above described primary steam power plant can be coupled with an ordinary stationary boiler plant. In this embodiment a chain grate stoker is shown. A sectional boiler, an existing fire tube or internally fired boiler or any other boiler with any desired heating method would also be suitable.

As illustrated in the drawings, the gases are delivered from the common furnace chamber 20 35 by way of the conduit 21 into the rotating steam generator 22, and leave it by way of conduit 23. They then flow through the tube bundle of the bent tube boiler and thus give off their heat for the preliminary heating of the liquid contained 40 in the bent tube boiler.

The steam produced in the rotating steam generator 22 then reaches the prime mover 15 which is arranged on the same shaft with the steam generator 22 and is expanded to a greater or less 45 degree in this prime mover.

The expanded steam now leaves the prime mover 15 by way of conduit 24 and flows through the serpentine tube bundle 25 provided in the upper drum of the bent tube boiler, where it is 50 condensed. The condensate flows through the conduit 26 to the rotating steam generator 22, where it evaporates in order again to start on its path through the circuit as described.

The pressure at which the steam is exhausted 55 from the prime mover 15 and delivered to the coil 25 determines the pressure at which the steam is generated in the bent tube boiler 27. In general it is advantageous to exhaust the steam from the prime mover at a higher pressure than the 60 pressure of the secondary steam in the boiler 27 as there is obtained in this case particularly favorable heat transfer conditions and very simple constructive possibilities. However, these conditions are determined also by the kind of liquids 65 that are to be vaporized. These conditions may vary according to whether a single stage, two stage or multistage system is under consideration. Moreover, consideration must also be given to the difference between the pressure of the primary steam generated in the steam generator 22 on the one hand and the secondary steam generated in the boiler 27 on the other hand, since the pressure of the primary steam in the coil 25 in the upper drum of the bent tube boiler 27 must 70 75

be so high that a "heat drop" between the condensing primary steam and the generated secondary steam takes place. This "heat drop" must be sufficient for the generation of the secondary steam.

The combination of the primary and secondary plants is especially advantageous in the operation with mercury vapor. The temperature of the mercury vapor, even over a considerable range of expansion, is still so high that a steam plant must be added. In such a case mercury vapor would be produced and expanded in the power plant 22, 15 and would then, upon condensing and cooling, produce secondary steam in the boiler plant 27.

The generated secondary steam can then be utilized in a prime mover 28 which is either coupled with the prime mover 15 or is separately arranged. The whole apparatus can serve for the operation of a generator 29, or its energy can be utilized in some other manner. If no secondary steam is generated but only hot water is produced the plant can also be used under such operating conditions as are desired.

It is, however, not always necessary to operate the steam generator in such a way that evaporation of the liquid is complete and a drying as well as superheating of the vapor results. The pressure produced by centrifugal action can also be used to produce a circulation of the liquid through the tube system. Figure 7 illustrates the embodiment of this idea in a form which will serve as an example. As is to be seen in this drawing, the fluid to be vaporized travels towards the rotating steam generator from the elevated receptacle 4 through the conduit 30. A steam water mixture is then produced in the steam generator, which leaves the steam generator by way of stuffing box 7 and is led through conduit 31 to the elevated receptacle 4. A separation of the liquid and the steam takes place in this receptacle. The separated steam leaves the elevated receptacle 4 through conduit 32 to be conducted to a place of use while the unevaporated liquid is again delivered to the steam generator through conduit 30, in order again to start on the circuit as described.

The steam generator in this embodiment has no superheating coil 13 such as is illustrated in Figure 3.

Figure 5 also is different from Figure 3 in that the steam generated in tubes 1 is not conducted away through headers 12 arranged on shaft 6, but is withdrawn directly through hollow shaft 6.

Another embodiment of the invention is illustrated in Figures 8 and 9. The liquid to be vaporized in this case is delivered from the elevated receptacle not shown into the tube system 2 and then flows through the distributing headers 11 into the vaporizing tubes 1. These tubes are arranged staggered and may be of such form that due to the rotation of the steam generator a fan action is produced which effects the suction of the gases from duct 33 and its conveyance through the steam generator and its discharge through the outlet 35. It is, of course, possible to arrange the steam generator tubes 1 or the water inlet tubes 2 in other ways in order to produce this fan action. This arrangement has the advantage that the gases, for the purpose of increasing the heat transfer and therefore the specific steam generation, i. e. the steam generation per unit of surface, may be led through the steam generator with greater speed without ne-

cessitating the construction of a very expensive suction fan installation.

Such a method of producing combined heat exchange and fan action has the advantage that the losses resulting from eddies in the gas are regained as heat. Moreover, as the fan action is produced by the heat transfer elements themselves, a suction fan at the outlet of the generator with its attendant disadvantage of air infiltration and the resultant reduction of efficiency is avoided. In the present invention as the heat exchanger or steam generator itself draws the gases from the furnace and delivers them through the rotating heating surface a more uniform pressure is maintained throughout the gas flow and air infiltration is avoided. Such a heatexchanger has the advantage that it may operate without extreme draft loss through the heating surface without providing either a high force draft pressure or great suction in order to produce the necessary pressure drop for delivering the gases through the heating surface. In the steam generator of the present invention the pressure difference in the gases before and after the heating surface is only small and the resistance within the heating surface itself is overcome by the fan action of the rotating heating surface.

The embodiment of the invention, as shown in Figures 8 and 9, is also advantageous in providing flow of the flue gases in an axial direction through the heating surface elements arranged upon the shaft. The delivery of the heating gases may be accomplished by introducing them near the shaft at one end and discharging them at the circumference of the steam generator at the other end. By arranging the steam generating elements in a staggered screw-like arrangement with the elements themselves so formed or with devices so attached to the element that the requisite form of fan blade is provided, the forward movement of the gases may be accomplished. In the embodiment shown in Figure 8 for example, the gases coming from the furnace enter the heating surfaces through duct 33 at the left side of the rotating steam generator. At the right side of the steam generator the flue gases are forced out through the waste gas passage 35.

The tubes 1 and 2 may be provided with fins 70 as shown in Figure 10. These tubes are also illustrated in an enlarged view as shown in Figures 11 and 12. As will be seen from Figures 11 and 12, the planes of fins 70 are inclined to the axis of the shaft 6 and these fins produce a movement of the gases in the direction of the arrows as shown in Figure 10 or axially along the shaft 6 when the proper direction of rotation is given to the shaft 6. By greater or less inclination of the fins to a plane at right angles to the axis of rotation, the rate of delivery of the flue gases may be modified. As will be seen from Figure 12, the tubes are arranged in staggered relation along the shaft and circumferentially around the shaft. It will be clear from the above description and from the drawings that the transfer of heat from the gases to the tubes 1 and 2 is effected while at the same time these tubes produce the necessary flow of the gases into contact with said tubes. If provision is made for the introduction of the gases into the casing 34 at a point near the shaft as shown in Figure 11 the centrifugal fan action of the tubes 70 as at 80 acting upon the gases may be utilized to produce flow from a point at the circumference of the casing, in which case the fins may be omitted.

The rotating steam generator arranged for fan 75

action as described is suitable not only for direct fired steam generating plant but also may be used for waste heat installations, as such steam generators require a draft to accomplish the movement 5 of the gases over the heating surfaces. The invention is also applicable to other installations where heat is transferred to a fluid flowing through heating elements, which elements are rotated and in which the rotation may be used for 10 causing movement of the fluid to be heated or of the gases for heating or both.

It is to be seen from the above explanations that the process of generating steam according to the invention can be used in all cases where steam is 15 to be produced from water or from other fluids, for example mercury, for power or heating purposes. In consequence of the easy and space-saving construction of the steam generator of the invention it can be used not only for stationary and marine 20 boiler construction, but also for any kind of vehicles, for example automobiles, locomotives or airplanes.

What is claimed is:

1. A heat exchanger comprising a heat ex- 25 change element of the type providing a defined path in which a fluid is heated while flowing therein, means for delivering the fluid to be heated to said element for flow therein, means for withdrawing the heated fluid from said element, means 30 for revolving said element as a whole about an axis of revolution, said element being so arranged with respect to said axis of revolution that the fluid is delivered to said element adjacent said axis and so that the centrifugal force of said revolution 35 acts upon said fluid in at least a part of said element so as to tend to produce flow of the fluid outwardly from said axis in said part, and means for so limiting the heating of said part of said element as to prevent the expansion of said fluid 40 while in said part to a state so expanded as to interfere substantially with the flow producing action of the centrifugal force in said part while heating a portion of said element succeeding said part in the direction of flow of the fluid to a state 45 sufficiently expanded so that said centrifugal force acting upon said unexpanded fluid may cause said fluid to flow through said element and to discharge said expanded fluid therefrom.

2. A vapor generator comprising a vapor generating element of the type in which the vapor is 50 generated from liquid flowing therein, means for delivering liquid to said element for flow therein, means for withdrawing vapor from said element, means for revolving said element as a whole about an axis of revolution, said element providing a continuous path of flow from one end thereof to the other and being arranged so that the liquid inlet end thereof is adjacent said axis and so that the liquid under the action of the centrifugal 55 force of said revolution flows through a portion of the element outwardly from said axis, and means for so limiting the heating of said portion of the element as to prevent the generation in said portion of the element of vapor from said liquid 60 in amount sufficient substantially to interfere with the flow producing action of the centrifugal force upon said liquid while heating a succeeding portion of said element sufficiently to generate therein vapor from the liquid delivered thereto, 65 said vapor and any liquid in excess thereof being caused to flow through said succeeding portion under the force created by the centrifugal action upon said liquid in said portion in which the liquid flows outwardly from the axis.

70 3. A steam generator comprising a steam gen-

erating element of the type providing a definite path in which the steam is generated from water flowing therein, means for delivering water to said element for flow therein, means for discharging steam from said element, and means for revolving said element as a whole about an axis, the arrangement of said element with respect to said axis being such that the water is delivered to said element adjacent said axis and under the action of the centrifugal force of the 10 revolution is caused to flow therein outwardly from said axis while the steam is withdrawn from the other end of the element, and means for so heating said element as to generate steam therein and to discharge steam therefrom while 15 substantially preventing the generation of steam in said portion of the element in which the water flows outwardly from said axis.

4. A vapor generator comprising a vapor generating element of the type providing a defined 20 path in which the vapor is generated from liquid flowing therein, means for delivering liquid to one end of said element for flow therein, means for revolving said element about an axis of revolution whereby the liquid within said element is 25 subjected to the action of centrifugal force, said element being so arranged with respect to said axis of revolution that the liquid is delivered to said element adjacent said axis and is caused by the centrifugal force to flow through said element outwardly from the axis with a concomitant increase of its pressure, means for generating vapor in said element from the liquid at said increased pressure while flowing in said element, and means for preventing during said outward 30 pressure-increasing flow heating of the liquid to such a degree as to cause the formation of vapor in an amount sufficient substantially to interfere with said increase in pressure of the liquid.

5. A steam generator comprising a steam generating element of the type providing a defined path in which the steam is generated from water flowing therein, means for delivering water to one end of said element, means for revolving said element about an axis not coincident with the 40 path of flow provided by the element, said element being so arranged with respect to said axis that the water inlet end thereof is adjacent the axis and so that the water delivered thereto is caused by centrifugal force to flow outwardly 45 from said axis in at least a portion of the element adjacent said water inlet end thereof, said element having a portion succeeding said first portion and subjected to heat sufficient to generate steam from water flowing therein, and means 55 for so limiting the heating of said first portion as to prevent the generation of steam therein in amounts sufficient to interfere with producing by said centrifugal force in the water flowing outwardly therein a pressure capable of causing flow 60 of water together with the steam generated therefrom in said succeeding portion and to discharge the steam therefrom.

6. A steam generator comprising a tube arranged substantially radially with respect to an 65 axis of rotation, means for delivering water to said tube at the end thereof adjacent said axis, means for rotating said tube about said axis to cause the water under the action of centrifugal force to flow in said tube outwardly from said 70 axis, means connected to the end of said tube remote from the axis and providing succeeding the outward flow in said tube a path of flow in heat exchanging relation to a source of steam generating heat for the water discharged from 75

said end of the tube remote from said axis, and means for so limiting the generation of steam in said radial tube as not to interfere with the action of said flow producing centrifugal force upon the water to cause said water to be delivered into and to flow in said path in heat exchanging relation to said source of steam generating heat.

7. A steam generator comprising a tube arranged substantially radially with respect to an axis of rotation, a second tube arranged substantially radially with respect to said axis, a connection between the ends of the tubes remote from the axis, means for applying steam generating heat to said second tube, means for delivering water to said first mentioned tube at the end thereof adjacent said axis, means for removing the generated steam from the end of said other tube adjacent said axis, and means for rotating the tubes about said axis at a speed such that the water in the first mentioned tube and the steam and any water in the second mentioned tube are subjected to the action of centrifugal force, and the difference in the pressure produced by the differences of the centrifugal forces resulting from the difference between the weight of the water in the first tube and the weight of the steam and any water in the second tube causes flow of the water outwardly from said axis in said first tube and flow of the steam and any water inwardly toward said axis in said second tube.

8. A steam generator comprising a plurality of tubes arranged substantially radially with respect to an axis of rotation, means for applying steam generating heat to some of said tubes while limiting the amount of heat applied to others of said tubes to avoid steam generation, means for delivering water to the ends of said tubes subjected to a limited amount of heat at the ends thereof adjacent said axis, means for withdrawing the generated steam from the ends of said other tubes at the ends thereof adjacent said axis, means connecting the ends remote from the axis of said tubes subjected to limited heat with the ends remote from the axis of said tubes subjected to steam generating heat, and means for rotating all said tubes about said axis at a speed sufficient to produce a pressure in the water in said tubes subjected to limited heat at least equal to the pressure of the generated steam, whereby the water delivered to the ends of the tubes adjacent to the axis is caused to flow outwardly through said tubes subjected to limited heat and to be delivered to said tubes subjected to steam generating heat for generation of the steam therein substantially at said pressure.

9. A steam generator comprising a plurality of steam generating elements of the type in which the steam is generated from water flowing therein, a shaft upon which said elements are mounted, means for delivering water to said elements at one end of each thereof, means for revolving said elements in a group as a whole upon said shaft acting as an axis of revolution, said elements each providing a defined path of flow from the water inlet end thereof to the other end thereof and being arranged so that the water inlet ends thereof are adjacent said shaft and with a portion of each element adjacent its water inlet end extending outwardly from said shaft, whereby the water within said portion of each element is subjected to the action of centrifugal force acting generally in a direction along the path of flow provided by said portion of said element, means

for limiting the heating of said portion of the element so as to prevent the generation in said portion of each element of steam in amount sufficient substantially to interfere with the flow impelling action of said centrifugal force along said path of flow, and means for generating steam in a succeeding portion of each element from water as it is impelled to flow under the action of the centrifugal force of the water flowing in said first portion, and means for collecting the steam discharged from the elements under said impelling action.

10. Steam generator according to claim 9 in which the shaft is hollow in at least a portion thereof, and said elements have at least one end thereof connected to said hollow space to provide for flow of fluid through said space and through said tube in a direction determined by said flow impelling action of the centrifugal force.

11. Steam generator comprising a hollow shaft, at least two tubes each connected at one end thereof to said shaft and extending outwardly from said shaft as an axis, means for rotating said shaft and said tubes about said axis, means for delivering water to a portion of the hollow space of said shaft connected to one of said tubes, the other of said tubes being subjected to steam generating heat and being connected into a portion of the hollow space of said shaft separated from the portion of said hollow space into which the water is delivered, means connecting the outer ends of said two tubes to form therewith a defined path of flow from one hollow space of the shaft to the other, said tube to which the water is delivered being subjected to heat insufficient to generate steam in such amount with respect to the water contained in said tube as to prevent the development in said water by the action of centrifugal force of a force at the outer ends of said tube capable of impelling the water to flow through said connection and inwardly in said other tube together with the steam generated from the water and to discharge the generated steam into said other portion of the hollow shaft.

12. Steam generator according to claim 3 in which a plurality of the steam generating elements are arranged about an axis and in which are provided means for distributing the water to the individual elements so as to cause it to flow through the generator in a general direction parallel to said axis, and means for causing heating gases to flow over the heating elements in a direction generally parallel to the axis.

13. Steam generator according to claim 3 in which a plurality of the steam generating elements are arranged about an axis and in which are provided means for distributing the water to the individual elements so as to cause it to flow through the generator in a general direction parallel to said axis, and means for causing heating gases to flow over the heating elements in a direction counter to the flow of water.

14. Steam generator comprising a shaft, a plurality of tubular steam generating elements arranged with their lengths extending outwardly from said shaft and connected to said shaft at the inner ends, said elements being arranged in spaced relation about said shaft and being so formed and so positioned with respect to each other and to said shaft as to provide gas-propelling surfaces when said shaft is rotated upon its axis, means for rotating said shaft to produce flow of gases over said steam generating elements, and means for collecting the steam discharged from said steam generating elements.

15. Steam generator according to claim 14 in which the water to be evaporated is delivered along said shaft to the inner ends of said steam generating elements and is subjected in said elements to the action of centrifugal force due to the rotation of said elements upon said shaft to cause the water to flow through said steam generating elements.
16. Steam generator according to claim 14 in which the steam generating elements are in the form of tubes arranged radially about said shaft in staggered spiral relation thereto.
17. Steam generator according to claim 14 in which the steam generating elements are in the form of tubes arranged radially about said shaft in staggered spiral relation thereto, said tubes being provided with fins in such angular relation to a plane at the right angles to the axis of the shaft as to provide a gas-propelling surface.
18. Process of heating a fluid which comprises delivering the fluid to be heated into a positively defined path of fluid flow, subjecting the mass of said fluid while in said path to the action of centrifugal force tending to produce flow of the fluid along a portion of said path, limiting the heating of said fluid in said portion of said path to prevent expansion thereof while in said portion of the path to a state so expanded as to interfere substantially with the flow producing action of the centrifugal force of the fluid in said portion, and heating the fluid in a succeeding portion of said path to a state so expanded that the centrifugal force of said unexpanded fluid may cause flow through said succeeding portion of said path of the fluid delivered from said first portion and may cause discharge of the expanded fluid from said path.
19. The process of generating vapor from a liquid which comprises subjecting said liquid to the action of centrifugal force to increase the pressure thereof while so limiting the heating of the liquid as to prevent the generation from said liquid of vapor in amount sufficient to interfere with said increase in pressure and utilizing said pressure of the liquid to cause flow thereof in a defined path in heat exchanging relation to a source of heat for generating vapor from said liquid while flowing in said path.
20. Process of generating vapor from a liquid which comprises delivering the liquid into a path of liquid flow, subjecting said liquid in said path to the action of centrifugal force to cause said liquid to move in said path and to raise the pressure of the liquid, applying to said liquid at the increased pressure and while subjected to said centrifugal force heat sufficient to generate vapor therefrom at said pressure but limiting the heating of the liquid to prevent substantial generation of vapor from said liquid prior to its acquiring while flowing in said path said pressure under the action of the centrifugal force, and utilizing said pressure to cause flow of the water in said path in heat exchanging relation to the source of heat.
21. Process of generating vapor from a liquid in a vapor generating element of the type providing a defined path in which the vapor is generated from liquid flowing therein which comprises delivering to said element the liquid to be evaporated, revolving said element about an axis of revolution so as to subject the liquid in said element to the action of centrifugal force,
- causing said centrifugal force to move the liquid through the element outwardly from said axis and to raise the pressure of said liquid, so limiting during said outward movement of the liquid in said element the heating thereof as to prevent the generation of vapor in amount sufficient to interfere with raising the pressure of the liquid, utilizing said pressure to cause the liquid to flow through a portion of the element succeeding said portion in which the flow is outward from said axis, generating vapor from said liquid flowing in said succeeding portion, and utilizing the flow impelling action of said pressure to cause the vapor to flow inwardly toward said axis against the centrifugal force acting on said vapor.
22. Process of generating vapor from a liquid which comprises causing the liquid to flow in a predetermined path under the action of centrifugal force acting directly upon the mass of liquid flowing in said path to increase the pressure thereof, preventing prior to its acquiring said increased pressure heating of the liquid sufficiently to generate from said liquid vapor in amount capable of interfering with the increase of said pressure, passing said liquid while at said increased pressure and while subjected to centrifugal force acting directly on the mass thereof through a zone of vapor generating heat, and utilizing said pressure of said liquid to force the generated vapor to flow against the action of centrifugal force and to cause discharge thereof from said zone of vapor generating heat.
23. A vapor generator comprising a conduit having one end thereof adjacent an axis of revolution and extending from said end outwardly from said axis, a vapor generating element of the type providing a defined path of fluid flow, said element being subjected to vapor generating heat and being positioned with one end thereof adjacent said axis, so that said path of fluid flow extends inwardly toward said axis, means connecting said conduit and said element at a point remote from said axis to provide for fluid flow from one to the other, means for delivering the liquid to be vaporized to said end of the conduit adjacent said axis, means for revolving said conduit and said element about said axis, whereby the liquid in said conduit is subjected to centrifugal force tending to produce flow thereof outwardly in said conduit, means for preventing in said conduit the generation of vapor in such amount with respect to the liquid contained therein as to interfere with the development in said liquid by the action of the centrifugal force of a force at the outer end of said conduit capable of impelling the liquid through said connection and inwardly in said element together with the vapor generated therein and to discharge the vapor from the inner end of said element.
24. Process of heating a fluid which comprises delivering a liquid to be heated into a defined path of fluid flow, subjecting the mass of said liquid to the action of centrifugal force while in said path, limiting the heating of the liquid in a portion of said path to prevent substantial formation of vapor while subjecting the liquid in a portion of said path succeeding said first portion in the direction of the flow to vapor generating heat, so that the centrifugal force in the liquid acts to produce flow of the fluid in said path and to deliver the fluid therethrough.

HEINRICH VORKAUF.
